UNITED STATES PATENT OFFICE.

GEORGE W. GREGORY, OF SYRACUSE, NEW YORK.

IMPROVEMENT IN TRUSSES.

Specification forming part of Letters Patent No. 138,640, dated May 6, 1873; application filed April 30, 1873.

To all whom it may concern:

Be it known that I, GEORGE WILSON GREGORY, of Syracuse, in the county of Onondaga and State of New York, have invented a certain new and useful Truss and Fastening Attachment.

The first object of my invention is to enable the pad to be adjusted readily on the truss-plate; and it consists in providing the truss-plate with a series of end and central slots, from one to the other of which pads of various desired shapes may be applied, and the pad working in connection with this truss-plate when adapted for hernia has slots at about right-angles to the slots in the plate. The second object of my invention is to provide an attachment for readily connecting and disconnecting the straps and truss-plate; and it consists in a plate or frame provided with suitable buckle-like tongues to hold the straps or bands, and with a hook, projection, or opening to engage a slot, opening-hook, or post on the truss-plate or supporter; and I do hereby declare that the following specification taken in connection with the drawing furnished and forming a part of the same, is a clear and accurate description thereof.

Figure 1 is an outside view of the truss-plate; Fig. 2, a horizontal section of the same; Fig. 3, a view of the back of the pad as adapted for hernia. Fig. 4 is a longitudinal section of the same. Fig. 5 is a view of the fastening attachment; Fig. 6, a side view with buckle-like tongues upturned; Fig. 7, a view of a tongue removed from the plate. Fig. 8 is a modified form of fastening, having an opening instead of a hook; Fig. 9, a view of part of a strap with a piece attached to receive the hook represented by Fig. 10.

A represents the truss-plate, made preferably of hard India rubber or metal, and provided with ribs or projections to bear against the person, in order to prevent the plate from slipping and provide for ventilation. This truss-plate is provided with vertical slots *a a* at the ends, and with central slots *a'*. The slots *a* are to receive the screw or screws that secure pads adapted for hernia, and in form substantially as shown in Figs. 3 and 4, and the central slots are to provide for the attachment of umbilical pads, which are usually hemi-

spherical. In addition to these vertical slots, the truss-plate has either slots, as shown at *b*, or hooks, as shown at *c'*, to receive the hook of or engage the opening in the fastening-plate. The pad *B* is preferably perforated where it bears against the person, as at *f*; and its back is provided with slots about at right angles with slots in the truss-plate when the two are in position. Under these slots is placed a supporting-piece, *d*, for the head of the bolt *d'*, the screw-shank of which passes through the slot in the pad, and also through the vertical slot of the truss-plate from the ribbed side, and when in such position and properly adjusted the pad is confined by means of a thumb-nut, *e*, which is turned on said screw and against a washer that bears against the back of the truss-plate. The plate *A* when provided with the slots, as described and shown, admits of its being used as a double hernia truss or for right or left hand, and an umbilical truss; or without pads it may be used as a supporter. The fastening attachment consists of a frame, *G*, of suitable form, provided with buckle-like tongues *H*, which turn on the frame, and with a hook, *b'*, Figs. 4 and 5, or its equivalent, (and opening, *c'*) Fig. 8. The tongues turn on the frame. Two of these fastenings are usually used with each truss-plate, and the buckle-like tongues confine and hold the strap, which is passed about the body, and the end of the strap that is passed between the thighs. The back end of the last-mentioned strap is preferably provided with a hook, *I*, (see Fig. 10,) and this hook is engaged with an opening in a piece of leather, *i*, or other material, secured to the outside of the strap *J* which passes about the body. The fastening, when provided with a hook, as at *b'*, is engaged with the truss-plate through the openings *b* made in the truss-plate, or a plate attached to such truss-plate, and when the fastening is provided with the opening, as at *c'*, Fig. 8, then a hook, *c'*, is to be secured to or made to project from the back of the plate. The fastening-plate may be provided with projections *g* to bear against the truss-plate, in order to provide for additional leverage and press the pad closely to the person, and also to assist in preventing the truss-plate from being overturned.

I do not desire to confine myself to buckle-like tongues of the form shown, as any other well-known tongues may be employed instead. Nor do I wish to limit myself to the particular shape of hook or opening, as other shapes may be used.

By means of this fastening the truss-pad may be quickly fitted to the person, and be readily removed. The slots *a* at the center of the truss-plate might be of other shape than that shown, and one slot or opening might be sufficient for securing the umbilical pad.

Having thus described my invention, what I claim as new, and desire to secure by Letters Patent, is—

1. A truss-plate provided with the series of central and end openings, substantially as described, to provide for the attachment of pads, as set forth.

2. The corrugated truss-plate provided with the long vertical openings at its ends for attachment of a pad or pads.

3. The combination, with the truss-plate provided with the vertical end and central slots, of the pad provided with the transverse slots and with a screw-connecting device, substantially as described.

4. A detachable truss-fastening attachment, composed of a plate or frame provided with buckle-like tongues for confining the straps, and with a hook or equivalent to engage the truss-plate, substantially as described.

5. A detachable truss-fastening attachment composed of a plate or frame provided with buckle-like tongues and with a hook or equivalent to engage with the truss-plate, and with a projection at the back of the frame to bear against the other side of the truss-plate, for the purpose described.

GEO. WILSON GREGORY.
